Primary Examiner — Sheryl Lane*Assistant Examiner* — Kathryn Elizabeth Chambers(74) *Attorney, Agent, or Firm* — Lewis Roca Rothgerber Christie LLP(57) **CLAIM**

The ornamental design for a vehicle lamp as shown and described.

DESCRIPTION

FIG. 1 is a front, left-side and top perspective view of a vehicle lamp showing my new design;

FIG. 2 is a front, left-side and bottom perspective view thereof;

FIG. 3 is a front, right-side and bottom perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The dashed broken lines depict portions of the vehicle lamp that form no part of the claimed design.
